TELEPHONE SUBSTATION SYSTEM

Fritz Lubberger, Berlin, Germany, assignor to
 Siemens & Halske Aktiengesellschaft, Siemens-
 stadt, near Berlin, Germany

Application November 23, 1932, Serial No. 644,031
 In Germany January 27, 1932

20 Claims. (Cl. 179—18)

The invention relates to circuit arrangements for telephone substation systems in which the subscribers are in a position to receive incoming exchange calls as well as to switch other sub- 5 station subscribers' calls over to their own line.

The object of the invention is to ensure a satisfactory operation in such systems by providing the private branch exchanges with devices which will enable the subscribers themselves to choose 10 whether they wish to receive an incoming exchange call over the exchange line or prefer to switch an existing connection with another subscriber over to their own line.

An embodiment of the invention is shown in the 15 accompanying drawings:

Fig. 1 shows a substation telephone line and a pair of finder switches AS and HW in which this line terminates.

Fig. 2 shows the final selector LW linked to the 20 finder switches AS and HW and having access to the trunk line *a—b*.

Completing an incoming exchange connection

Upon the exchange calling a substation subscriber over the line *ab*, the alternating current sent out from the exchange energizes relay AR over windings I and II so that it closes its contact 1ar and consequently remains energized over: earth, battery, winding III, contacts 1ar, 2a, 30 earth, and by opening its contact 56ar prevents the exchange line from being seized for an outgoing call. The closing of contact 1ar at the same time closes the following circuit for the lamps L1 and L2 associated with the exchange 35 line taken into use: earth, contacts 2a, 1ar, lamp L1 or L2, battery, earth. These lamps L1 or L2, which are located, respectively, at stations designated to receive incoming calls, operate no matter which particular subscriber of the system is 40 being called. Exchange call signal lamps may also be provided for all the subscribers so that each substation can receive an incoming exchange call. A subscriber, for example T to whom the lamp L1 has been allocated, then receives the 45 call by lifting his receiver. The two-step relay R is energized over: earth, contacts 3r, 4g, the T-subscriber's line loop, contacts 5g, 6r, winding I of relay R, battery, earth. This relay R is energized in its first stage only and consequently 50 only opens its contact 9r and closes 7r and 8r. The closing of contact 8r prepares the test circuit over the c-wiper of the call finder AS, where- 55 as contact 7r closes a circuit for relay C as follows: earth, contacts 7r, 10r, 11pa, 12pl, relay C, battery, earth. Relay C is energized and by

means of contact 13c closes the following circuit for the rotary magnet DAS: earth, contacts 13c, 14g, 15pa, 16das, rotary magnet DAS, battery, earth. The rotary magnet DAS actuates its contact 16das and by means of this contact opens 60

the above-described circuit for the rotary magnet, so that they interact with each other and form a so-called self-interrupter circuit. The wipers of the call finder AS are continuously ad- 65

vanced until the test circuit prepared by contact 8r is completed. Said test circuit extends as follows: earth, contacts 17c, 18u, windings I and II of relay PA, c-wiper of the call finder AS set to the T-subscriber's line, contacts 8r, 19q, wind- 70

ing II of relay R, battery, earth. Relay PA is energized in this circuit and by means of contact 15pa opens the circuit for the rotary magnet DAS, at the same time short circuiting its winding I at contact 20pa for the purpose of guarding the sub- 75

scriber's line. In addition, relay R is energized in its second stage in the test circuit. This causes the calling circuit to be cut off at contacts 3r and 6r. Contact 10r is opened and prevents opera- 80

tion of the second call finder IIAS accessible over contact 31pa. The opening of contact 10r causes relay C to relapse but contact 32k maintains the test circuit independent of contact 17c due to the fact that relay J is energized over the subscriber's 85

line loop on the closing of contacts 22pa and 23pa and relay K also operates over: earth, battery, 90

relay K, contacts 34j, 30pl, earth. With the aid of relay PA the switch HW also is set to the sub- 95

scriber's line in the following manner: Relay PA causes the rotary magnet DHW of the switch HW to operate over: earth, contacts 26u, 27ph, 28pa, 29dhw, rotary magnet DHW, battery, earth. In 100

conjunction with contact 29dhw the rotary magnet operates as a self-interrupter and advances the wipers of the switch HW until the following

circuit has been completed over the d-wiper of HW and the e-wiper of AS: Alternating current 105

source of supply W, relay PH, d-wiper of HW, e-wiper of AS alternating current source of supply. Relay PH is an alternating current relay which, when energized, cuts off the circuit for the rotary magnet DHW of HW by opening its contact 27ph. 110

The lighting of the lamp L1 indicates to the subscriber T that the call has been put through over the line connected to contact 3 of the final selector LW. In order to set the final selector LW to this contact 3 the calling subscriber has to transmit three impulses which influence relay J. This relay in turn causes the rotary magnet DLW of the final selector LW to operate over: 110

earth, contacts 30pl, 33j, 34e, 35k, rotary magnet DLW, battery, earth. The circuit for relay K is cut off at contact 31j during the transmission of the three impulses but relay K in spite thereof 5 does not release being adapted to release with slow action. During the impulse series relay V is energized in parallel with the rotary magnet DLW over contact 36e and during this period maintains the test circuit for the final selector LW 10 open at contact 37v. Relay V releases at the end of the impulse series and the following test circuit for relay PL is then closed: earth, contact 37v, windings I and II of relay PL, c-wiper of the final selector LW in position 3, contacts 38ar, 39sp, 15 resistance W, battery, earth. Relay PL is energized in this circuit and by short circuiting its winding I at contact 40pl guards the seized line in known manner. Relay PL maintains relay K energized over contact 41pl independent of relay J while relay J is disconnected from the speaking leads due to the opening of contacts 42pl and 43pl and, by the closing of 44pl and 45pl, these leads are switched through in the final selector. The closing of contact 46pl causes a fresh call 20 initiation to be transferred to a second call finder IIAS when relay PA also is restored to normal during the connection as described in a later paragraph.

By the change-over operation on the part of contacts 42pl-45pl, the feeding of the subscriber's line is effected over the exchange line. Relay A connected to the b-lead is energized and at contact 2a opens the locking circuit for relay AR and also the circuit for the signal lamps L, 25 thus indicating to the subscriber T that he has been connected to the exchange line. Relay A maintains the test circuit over the c-wiper of the final selector over contact 46a independent of contact 38ar. The opening of contact 47a and closing of 48a prevents a connection from being set up in the outgoing direction which might otherwise be accomplished by the final selector being set to contact 9.

The connection with the calling exchange subscriber is now completed. If the subscriber who thus has been set to the calling exchange line is in a position to receive the call, no further switching operations are performed until at the end of the conversation when, on the receiver in the 30 subscriber's station T being replaced, relay A restores and at contact 46a cuts off the circuit for relay PL. This relay at contact 41pl opens the locking circuit for relay K which in turn breaks the test circuit for the call finder at contact 32k. 35 This causes relays PA and R to release. The rotary magnet DAS of the call finder AS operates over: earth, contact 49m, f-wiper of AS, contact 15pa, 16das, rotary magnet DAS, battery, earth, and continues to advance the wipers of AS until 40 they reach their normal position in which the above-described circuit is cut off over the f-wiper of AS. After the release of relays PA and K the rotary magnet DLW of the final selector LW is energized over: earth, d-wiper of the final selector LW, contacts 50pl, 51dlw, 52k, rotary magnet DLW, battery, earth, and interacting with its contact 51dlw operates as a self-interrupter and continues to advance the switch wipers until the 45 above-described circuit for the rotary magnet DLW is opened by the d-wiper of the final selector upon being restored to its normal position.

Setting up an outgoing exchange connection

Should the subscriber T require an exchange 50 connection the call finder AS is set to the call-

ing subscriber in the manner previously described. The subscriber, however, contrary to incoming calls, has to transmit seven impulses instead of three. These impulses influence relay J and consequently also the rotary magnet DLW of the final selector in the same way as in the previous case. The final selector is set to the 7th contact and at the end of the impulse series relay V, in the manner already described, is de-energized so that the following circuit is closed: earth, contact 37v, windings I and II of relay PL, c-wiper of the final selector LW in position 7, relay E, contact 53pl, earth. Relay E only

80

is energized in this circuit, opens its contact 36e and prevents an energization of relay V on the actuation of the rotary magnet DLW initiated by relay E over: earth, battery, rotary magnet DLW, contacts 35k, 54e, 51dlw, 50pl, d-wiper of the final selector LW set to the contact segment 55, earth. The rotary magnet advances the wipers of the final selector LW until they encounter an idle exchange line. It will be assumed that the exchange line connected to contact 9 is idle. The following circuit is then closed: earth, contact 37v, windings I and II of relay PL, c-wiper of the final selector LW in position 9, contacts 47a, 56ar, 57sp, relay SP, battery, earth. Relay PL is the first to operate

85

in this circuit, opens at contact 50pl the circuit for the rotary magnet DLW, maintains over contact 41pl the circuit for relay K and due to the through-switching operation carried out by contacts 44pl and 45pl causes relay A to be energized. It should be noted that relay E is so retarded in its operation that on the advance 100 from contact 7 it remains energized until all the contacts to which exchange lines are connected have been brushed in the final selector LW. Relay SP switches over the test circuit for the final selector LW by opening contact 57sp and closing 58sp. After the switching through has been completed in the final selector,

90

relay A connected to the b-lead has been energized and contact 58sp closed the test circuit extends over contacts 48a and 58sp. Relay SP 105 opens contact 39sp, thus preventing the exchange line from being seized if another final selector is set to contact 3.

100

At the end of the call and after the receiver has been replaced in the subscriber's station T, relay A restores and cuts off the test circuit for the final selector LW at contact 48a. This at the same time breaks the circuit for relay SP which, however, releases with slow action and does not permit a fresh seizure until the final selector LW as well as the switch AS has been restored to normal in the manner described in the previously specified method of completing an incoming exchange connection.

110

Inquiry connections or transferring an exchange call to another sub-station

115

If the subscriber T has been connected to the exchange line, whether having received the incoming exchange call or having set up the exchange connection himself, and now wishes to transfer the call to another substation, he momentarily depresses the key Ta. The differential relay B which is connected up in the feeding circuit for the substation T is then energized 120 and causes relay I to operate over: earth, contact 59b, relay I, battery, earth. Relay B is restored to normal when the subscriber T releases the depressed key and the following circuit for relay U is then closed: earth, contacts 60b 61I, 125

130

135

140

145

150

relay U, resistance W1, battery, earth. The circuit for relay I is cut off at contact 59b but this relay still remains energized until a locking circuit for relay U has been formed over contact 68g. Relay U causes relay Q to be energized over: earth, contact 62u, c-wiper of the switch HW set to the calling T-subscriber's line, relay Q, battery, earth. Relay Q over its contacts 63g and 64g closes a circuit for relay F, 10 extending as follows: earth, battery, winding I of relay Y, winding I of relay F, contact 65u, a-wiper of the switch HW set to the T-subscriber's line, contact 64q, the T-subscriber's line loop, contact 63g, b-wiper of the switch HW set 15 to the T-subscriber's line, contact 66u, winding II of relay F, winding II of relay Y, earth. Relay F operates in this circuit. It transmits current to relay G over: earth, contact 67f, relay G, battery, earth, so that relay U will be maintained energized over contact 68g in the following circuit: earth, contact 68g, relay U, resistance W1, battery, earth. Relay I does not release until relay G has operated and the locking circuit for relay U has been completed. Relay 20 U, at contact 69u, connects a choke across the exchange line and thereby prevents the release of the exchange device.

Relay Q causes relay R to be maintained energized over: earth, contact 70q, winding II of 30 relay R, battery, earth, and by opening contact 19q cuts off the test circuit over the c-wiper of the call finder AS so that relay PA relapses and the wipers of the switch AS are advanced in the manner described above until they have been 35 returned to their original position. Relay S which by opening contact 71s opens the test circuit for the call finder AS is energized in parallel with the rotary magnet DAS while said magnet operates. Immediately upon the switch 40 wipers of the call finder leaving the T-subscriber's contact the circuit for relay PH is opened over the e-wiper, resulting in the release of relay PH. Relay G causes a switching-over operation to be performed at contacts 72g—75g. The subscriber T is now in a position to set the call 45 finder AS to the subscriber who is going to receive the exchange call. The subscriber T for the purpose of setting the switch AS transmits an appropriate impulse series which influences 50 relay F. Relay F in turn transmits the impulses to the rotary magnet DAS over the following circuit: earth, contacts 76f, 77pa, relay M, contact 78g, rotary magnet DAS, battery, earth. Relay S, opening its contact 71s, is influenced 55 in parallel with the rotary magnet DAS. Relay G due to its slow action does not relapse while contact 67f is intermittently opened according to the impulse series. At the end of this impulse series relay S is deenergized so that a test circuit— 60 unless the subscriber's station is busy—can be completed, extending as follows: earth, contacts 79y, 71s, 80u, windings I and II of relay PA, contact 81m, d-wiper of the switch AS set to the contact associated with the subscriber required 65 from the substation T, contacts 9r, 19q, winding II of the above-mentioned subscriber's relay R, battery, earth. In this circuit relay R associated with the subscriber required from the substation T is first energized and due to the 70 opening of contact 9r and closing of 8r a test circuit is completed over the c-wiper independent of the d-wiper of the switch AS and contact 81m. Relay PA completes the guarding by closing its contact 20pa and the switching through at contacts 22pa and 23pa. The ringing signal to the 75 required subscriber is transmitted in the following manner. Relay F closes the following circuit: earth, contacts 82f, 83o, relay N, relay interrupter RU, battery, earth. The relay interrupter RU causes relay N to be energized at definite intervals so that it applies ringing current to the leads a and b by opening its contacts 84n and 85n and closing 86n and 87n. When the subscriber accessible over the call finder AS lifts his receiver, relay O operates in the ringing pause in the following circuit: earth, battery, winding I of relay X, winding I of relay O, contacts 74g, 84n, 22pa, d-wiper of the switch AS set to the subscriber's line, to whom the exchange call is being transferred over a corresponding contact 5q, subscriber's line loop, contact 4q, b-wiper of AS, contacts 23pa, 84n, 75g, winding II of relay O, winding II of relay X, earth. Relay O only operates in this circuit and at contact 83o opens the circuit for relay N. Relay X is a differential relay and is not energized in series with relay O. The two substation subscribers are now connected with each other. If the subscriber who has been called over the switch AS wishes to take over the exchange call, this is carried out by momentarily depressing the key provided at the station reached over the switch AS. The momentary depression of this key causes the differential relay X in this subscriber's feeding circuit to operate so that relay II in turn is connected to battery over: earth, contact 88x, relay II, battery, earth. Relay II is a slow acting relay and remains energized for a short time after relay X has been restored to normal on the release of the key Ta. When the subscriber releases the key Ta and before relay X restores, relay U is short circuited over contacts 89x and 90II so that it relapses after a short period and at contacts 65u and 66u opens the circuit for relay F. This relay, at contact 67f, opens the 115 circuit for relay G, thus causing this relay G to relapse. The change-over at contacts 72g—75g is then restored and the speaking connection between the subscriber T and the other subscriber accessible over the switch AS is cut off. The subscriber reached over the switch AS has now been connected to the exchange line. On the release of relay U the locking circuit for relay PA extends over contacts 32k, 18u, etc. At the same time relay U at contact 62u opens the circuit for 120 relay Q, which opens its contacts 63g and 64g and closes 4q and 5q. The opening of contacts 70q deenergizes the T-subscriber's relay R if the subscriber T who was first connected to the exchange line meanwhile has replaced his receiver. 125 Due to the release of relay U and the energization of relay PA in the test circuit for AS the rotary magnet DHW of the auxiliary switch HW is again energized and the switch HW is set to the subscriber to whom the subscriber T has transferred the call over the switch AS and in exactly the same manner as that previously described for the subscriber T. The circuit for the rotary magnet DHW is again opened on the energization of relay PH. At this moment the other subscriber is connected to the exchange line in the same manner as that in which the subscriber T was connected up before the transfer took place.

If the subscriber T, while being connected to the exchange line, whether in outgoing or incoming traffic, wishes to set up an enquiry connection and at the end thereof be transferred back to the exchange line again, said subscriber T after having finished the enquiry call, momentarily depresses the key, thus causing the dif- 140 150

ferential relay Y in the test circuit to be energized. Relay Y at contact 79y opens the circuit for relay PA, which therefore restores and causes the switch AS set to the subscriber required by the subscriber T to advance its switch wipers until they have been restored to normal. The subscriber T now causes the switch AS to be set to his own line contact. He depresses his key Ta once more, thus causing relay Y to be reenergized and relay U to release due to short circuit in the following manner: Relay Y closes its contact 91y and thereby causes relay II to operate over: earth, contacts 91y, 92u, 93ph, relay II, battery, earth. Relay II remains energized over contact 94II independent of contact 92u. Relay II closes its contact 90II and causes relay U to be short circuited over earth, contact 89x and 90II, whereupon it replapses after a short period. Relay U upon its release cuts off the circuit for relay Q.

Due to the release of relay Q the T-subscriber's line is switched over from contacts 63q and 64q to 4q and 5q. Relay Q connects winding II of relay R to the c-wiper of AS over contact 8r, so that a circuit for relay PA is closed as follows: earth, battery, winding II of relay R, contacts 19q, 8r, c-wiper of AS set to the subscriber T, windings II and I of relay PA, contacts 18u, 32k, earth. Relay PA causes the previously described switching operations such as the switching through, guarding, etc., to be performed.

The relapse of relay U causes the circuit for relay F which extends over contacts 65u and 66u to be cut off.

When relay F is deenergized, relay G also relapses and the changeover at contacts 72g—75g is then effected whereupon the subscriber T is again connected to the exchange line as prior to the enquiry connection being set up over the switch AS.

In addition, it should be noted that relay II has a greatly retarded release with the result that even after the subscriber's line has been switched over from contacts 63q and 64q to contacts 4q and 5q, windings I and II of relay B are still short circuited at contacts 95II and 96II until relay II has been released and relay B consequently cannot be influenced as a result of the momentary depression of the key and the already completed connection with the exchange line over the switch AS.

What is claimed is:

1. In a telephone system, two lines, a trunk, a switch, means controlled over one of said lines for operating said switch to connect the line with said trunk to answer an incoming call over said trunk, means controlled over said one line for reoperating said switch to interrupt the connection with the trunk and to establish a connection between said two lines, and means controlled over the other of said lines for operating said switch to interrupt the connection between the two lines and to establish a connection between said other line and said trunk to receive the incoming call.

2. In a telephone system, two lines, a trunk, a switch, means controlled over one of said lines for operating said switch to associate the line with said trunk to answer or extend a connection thereto, means controlled over said one line for reoperating said switch to establish a connection between said two lines and to hold up the trunk connection, and means controlled over the other of said lines for interrupting the connection between the two lines and for associating said other

line with the trunk to take over the held-up connection.

3. A telephone system as claimed in claim 1 in which the switch is initially operated non-directively and reoperated directly.

4. A telephone system as claimed in claim 1 in which the reoperation of the switch is controlled jointly by a key and a calling device associated with the line effecting the initial operation of the switch.

5. In a telephone system, a finder switch and means for operating it to connect with a calling line, a second finder switch and means for operating it to connect with the calling line, and means controlled over the line for connecting the two finder switches together.

6. In a telephone system, a finder switch and means for operating it to connect with a calling line, a second finder switch and means for operating it to connect with the calling line, means controlled over the line for interconnecting the two finder switches, and means responsive to said interconnection for restoring the first finder switch to normal position.

7. In a telephone system, a finder switch and means for operating it to connect with a calling line, a second finder switch and means for operating it to connect with the calling line, means controlled over the line for interconnecting the two finder switches, and means controlled over the line for reoperating the first finder switch to extend a connection to a called line.

8. In a telephone system, two finder switches, means for operating both switches to connect with a calling line, means for releasing one switch while maintaining the connection with the other switch, and means for reoperating said one switch to extend a connection from the calling line to a called line.

9. In a telephone system, a line, a finder switch, means responsive to the initiation of a call on said line for operating said switch to connect with the line, a second finder switch, means controlled by said first switch for operating said second switch to connect with the line, means for momentarily unbalancing the line, and means responsive to said unbalance for releasing said first switch and for connecting the two switches together.

10. In a telephone system, a first switch, a second switch normally connected with the first switch, means for operating the first switch to connect a calling line with the second switch, means for operating the second switch to extend a connection, a third switch and means for operating it to connect with the calling line, means controlled over the line for disconnecting the first switch from the second switch and for temporarily connecting the first and third switches, and means for holding up the connection extended through the second switch while the first and third switches are interconnected.

11. In a telephone system, a first switch, a second switch normally connected to the first switch, means for operating the first switch to connect a calling line to the second switch, a third switch and means for operating it to connect with the calling line, means controlled over the calling line for disconnecting the first switch from the second switch and for interconnecting the first and third switches, means controlled over the calling line for reoperating the first switch to extend a connection to a called line, and means controlled over the calling line or the called line for disconnecting the first switch

from the third switch and for reconnecting it to the second switch.

12. In a telephone system, a first switch, a second switch normally connected to the first switch, means for operating the first switch to connect a calling line to the second switch, a third switch and means for operating it to connect with the calling line, means controlled over the calling line for disconnecting the first switch from the second switch and for interconnecting the first and third switches, means controlled over the calling line for reoperating the first switch to extend a connection to a called line, and means controlled over the called line for disconnecting the first switch from the third switch, for reconnecting the first switch to the second switch, and for operating the third switch to connect with the called line.

13. In a telephone system, two finder switches, means for operating one of said switches to hunt for and connect with a calling line, means controlled by said one switch for operating the other switch to connect with the line, means for releasing said one switch while maintaining the connection between the other switch and the line, and means controlled over the line for directly operating said one switch to extend a connection from the line to a called line.

14. In a telephone system, a line, a switch, means responsive to the initiation of a call on the line for operating the switch to hunt for and connect with the line, means for establishing an auxiliary connection between the switch and the line, and means controlled over the line and said connection for reoperating said switch to connect with a second line.

15. In a telephone system, two finder switches, a line having two branches, means responsive to the initiation of a call on the line for operating one switch to connect with one of said branches,

means responsive to said connection for operating the other switch to connect with the other of said branches, and means controlled over the line for controlling the connection of said branches to the line.

16. In a telephone system, two finder switches, a line having two branches, means responsive to the initiation of a call on the line for operating one switch to connect with one of said branches, means responsive to said connection for operating the other switch to connect with the other of said branches, and means for extending a connection from the line over said one branch and said one switch or over said other branch and both of said switches in tandem.

17. In a telephone system, a line, two finder switches, means responsive to the initiation of a call on the line for operating both switches to connect with the line, and means for completing the call through one switch alone or through the two switches connected in tandem.

18. In a telephone system, a switch, a trunk having two branches, means for operating said switch to connect with the trunk via one branch to answer an incoming trunk call, and means for operating the switch to connect with the trunk via the other branch to extend an outgoing trunk call.

19. A telephone system as claimed in claim 18 in which the switch is entirely directive operated to connect with one branch of the trunk and is both directly and non-directively operated to connect with the other branch of the trunk.

20. A telephone system as claimed in claim 18 in which the switch is one of a plurality of similar switches and is taken into use responsive to a subscriber lifting his receiver to answer or extend a call.
